FIG.2

FIG.12

FIG.10

FIG.11

FIG.9

FIG.7

FIG.8

FIG. 1 is a front elevation of binoculars in an open position, showing our new design;

FIG. 2 is a top plan view thereof;

FIG. 3 is a side elevation thereof;

FIG. 4 is a front elevation of the binoculars in a closed position;

FIG. 5 is a top plan view thereof;

FIG. 6 is a side elevation thereof;

FIG. 7 is a front elevation of a modified form of the binoculars in an open position;

FIG. 8 is a top plan view thereof;

FIG. 9 is a side elevation thereof;

FIG. 10 is a front elevation of the modified form of binoculars in a closed position;

FIG. 11 is a top plan view thereof; and

FIG. 12 is a side elevation thereof.

This is a continuation of design applications Ser. No. 427,412, filed Dec. 21, 1973, and Ser. No. 427,414, filed Dec. 21, 1973, and now both abandoned.

We claim:

The ornamental design for binoculars, as shown and described.
